UNITED STATES PATENT OFFICE.

FRED J. GOWING, OF SACKET HARBOR, NEW YORK, ASSIGNOR OF ONE-HALF TO JEROME B. ROSEBOOM, OF NOGALES, ARIZONA TERRITORY.

PROPELLER.

No. 913,951.

Specification of Letters Patent.

Patented March 2, 1909.

Application filed January 16, 1907. Serial No. 352,636.

To all whom it may concern:

Be it known that I, FRED J. GOWING, a citizen of the United States, residing at Sacket Harbor, in the county of Jefferson and State of New York, have invented certain new and useful Improvements in Propellers, of which the following is a specification.

This invention relates to improvements in propellers, designed for use in connection with all forms of power driven water craft, and which may also be employed in the propulsion of air-ships and the like. And the invention relates particularly to a two-blade propeller for use in driving and operating high-speed vessels.

The object of the invention is to provide a propeller wheel which is simple, strong, effective and inexpensive, and wherein a greater amount of power may be obtained and therefore a greater speed may be imparted to a boat or like craft, at the expenditure of less fuel and energy than by the use of any other device of the class.

A further object is to provide a propeller which will operate with greater steadiness, higher speed, and with less slip or loss of effective propelling power than the old forms of wheels, and a further object is to provide a wheel of the class wherein its peculiar design and structure renders it possible to greatly increase the size and lead of the blades, without necessitating any increase in the driving power.

The various features and parts of my invention will be understood from the detail description which follows, as well as by reference to the accompanying drawing, which forms a part of this specification, and in which—

Figure 1 is a side elevation, showing my propeller applied to the stern of a boat. Fig. 2 is a rear view of the propeller, taken on the line 2—2 of Fig. 1, showing the peculiar form of the blades. Fig. 3 is a sectional view of one of the blades taken on the line 3—3 of Fig. 2, showing a slight curve in the outer end of blade. Fig. 4 is a plan view, showing the great lead or angle of the blades.

Fig. 5 is a section on the line 5—5 of Fig. 2. Fig. 6 is a section on the line 6—6 of Fig. 2. Fig. 7 is a section on the line 7—7 of Fig. 2. Fig. 8 is a section on the line 8—8 of Fig. 2.

Similar characters of reference are assigned

to corresponding parts throughout the several figures.

In the drawing, I have shown a propeller wheel having two blades A and B, which are preferably formed integrally with a central hub C, having a circular hole D through its center, for use in applying the wheel to a driving shaft E, which may be operated by any source of power, such as an engine or motor.

F, F represent the cutting or leading edges of the respective blades. These are formed sharp and substantially straight away from or tangent to the outer curved surface of the hub, extending thus for a distance equal to nearly the whole length of the blades. The cutting edges of the blades, it will be observed, extend to and are even or in line with the face of the inner end of the hub, and they are substantially at right angles to the axis of the hub or wheel. The trailing edge G of each blade is formed in a large irregular curve, but the middle of the blades does not extend rearwardly beyond the outer end of the hub. The outer half of each blade is only slightly curved or dished, as shown in Fig. 3, while the other portion of the blade next to the hub is twisted or curved into almost a half circle. The inner end of the blades, where they are joined to the hub, preferably extend the full length of the hub, and each blade from the point H at the front end of the hub to the point I at the rear end of the hub describes a spiral line or compound curve extending half way around the hub.

Under the construction of my wheel, there are no shoulders or corners in the vicinity of the hub to be exposed to the water and thereby offer resistance to the forward or rotary movement of the wheel.

When my wheel is applied to a boat and set in motion, the long straight leading edges F of the blades cut the water throughout their full length in an even and regular manner. The outer ends of the blades being nearly flat, cut the water with little or no resistance, and as the wheel revolves the blades worm their way into the undisturbed mass of water in front of the wheel, and owing to the increasing concavity of the blades from their points to the hub, the water displaced by the cutting edges is forced inwardly and rearwardly and is discharged directly astern of the hub, leaving

the blades at or near the points I. During the operation of the wheel, owing to the peculiar form and disposition of the blades, having the long straight cutting or leading edges, there is practically no churning of the water as the wheel revolves, and there is apparently no slip or loss of motion, such as commonly occur where the older makes of propellers are used. My wheel is therefore more powerful, and capable of driving a boat at higher speed because of the elimination of resistance and slipping.

When my wheel is first set in motion and the boat begins to move forward, there is an apparent vacuum or void formed directly behind the wheel center; but the said vacuum only lasts for an instant, or long enough for the water displaced by the blades to be forced into the hollow space, after which a constant stream of water will flow rearwardly and keep it filled. The vacuum referred to plays a very important part in the successful operation of my propeller, for the reason that it affords a ready and effective way of disposing of the water displaced by the propeller blades, which require some such means for its disposition in order to prevent the churning of the water and the consequent retarding of the movement of the vessel by reason of the loss of effective propelling power and the resistance heretofore referred to. My experience shows that a propeller which operates in water which is constantly churning or boiling imparts less power to a boat, than when the water is simply cut and then discharged astern in a direct manner, from the center of the wheel, in a steady stream equal to the volume displaced and under conditions of least resistance as described. The vacuum-like space which occurs behind the hub of the wheel at the instant the boat starts forward, affords a receptacle into which the water may be forced in the first place without encountering any resistance, and after the currents of water begin to fill the said void, it will thereafter continue to flow astern in a steady and free stream, with practically no increase of resistance as the speed of the boat increases. Under the construction and operation of my propeller, the vacuum which occurs directly behind the wheel center cannot be prolonged for more than a moment, and therefore cannot exert any back-draft or suction to hinder the forward travel of the craft.

There are few power driven or propelled boats in which the vibration and jar from the propelling mechanism is not plainly felt by the occupants, no matter where they chance to sit or stand, and it is one of the principal objects of my invention to provide a wheel which will effectually remedy this annoying and injurious defect. To this end,

the blades of my propeller are made very nearly the same width for at least the length of the straight cutting edges, and that feature, taken with the gradually increasing concavity or dishing of the blades from their tips K to the point where they are joined to the hub, causes the wheel to rotate in a steady manner, without any perceptible vibration or chatter, and thereby produces an effect which is not only very pleasing and desirable, but which also prevents racking and otherwise injuring the craft.

During the rotation of blades A and B, the water displaced by them is carried or flows across the blades in substantially the course indicated by the arrows J, shown in Fig. 2.

It will be observed that blades A and B, where they are joined to the hub, have a greater width than the length of the hub, because they are disposed or formed in a spiral line. This feature is of great importance, because it not only adds strength to the blades, but it also serves to prevent the blades from vibrating, wabbling, or otherwise yielding to the great strain resulting from their being driven through the water at a high rate of speed.

Owing to the manner in which I construct and dispose the parts of my propeller, the blades are capable of being applied to the hub at an angle which will give a lead nearly one-third greater than I find on any of the wheels now in use, and by reason of the fact that my blades are made broader and longer proportionally than the others, they exert a greater propelling power, operate more steadily and evenly, and from actual tests of my wheel, in connection with the same engine and boat, I have been able to reduce the running time over a measured course at least thirty per cent., as compared with the wheels generally in use.

I have shown but two blades on my propeller, but three or four blades may be employed with good results; although for high speed boats, in connection with which I intend to use my wheel, I prefer to employ only two blades constructed and applied as herein shown and described, as they are adapted for operation at higher speed, because they offer less resistance and therefore require lighter engines and less fuel and energy for their operation.

It is obvious that some changes or modifications may be made in the structure or form of my wheel, without departing from the spirit of the invention, and I therefore do not restrict myself to the precise construction and arrangement as herein shown and described.

Having thus described my invention, what I claim as new and desire to secure by Letters Patent, is—

A two blade propeller, comprising a central

hub, and a pair of oppositely disposed concaved blades, the said blades having a long straight cutting edge extending at right angles to and flush or in the same plane with one end of said hub, and having a width greater than the length of said hub for a distance equal to the length of said cutting edges, the concavity of said blades gradually increas-

ing from at or near the tips thereof to the points where they are joined to the hub. 10

In testimony whereof I affix my signature in presence of two witnesses.

FRED J. GOWING.
